UNITED STATES PATENT OFFICE.

CARLETON ELLIS, OF WHITE PLAINS, NEW YORK, AND KARL P. McELROY, OF WASHINGTON, DISTRICT OF COLUMBIA, ASSIGNEES TO FIREPROOF PRODUCTS COMPANY, A CORPORATION OF NEW JERSEY.

PROCESS OF CHLORINATING ORGANIC BODIES.

No. 914,251.

Specification of Letters Patent.

Patented March 2, 1909.

Application filed January 12, 1906, Serial No. 295,730. Renewed October 6, 1908. Serial No. 456,416.

To all whom it may concern:

Be it known that we, CARLETON ELLIS and KARL P. McELROY, citizens of the United States, residing, respectively, in 5 White Plains, county of Westchester, State of New York, and Washington, District of Columbia, have invented certain new and useful Improvements in Processes of Chlorinating Organic Bodies; and we hereby declare 10 the following to be a full, clear, and exact description of the same, such as will enable others skilled in the art to which it appertains to practice and use the same.

This invention relates to improvements in 15 processes of chlorinating organic bodies, and consists in a new and useful method of treating certain aromatic hydrocarbons and other organic bodies to obtain a great variety of chlorinated products susceptible of economic 20 use; all as more fully hereinafter set forth, matters of novelty being particularly pointed out in the appended claims.

We have discovered that if certain aromatic hydrocarbons, and particularly those 25 containing a plurality of rings, or polycyclic, are chlorinated a wide variety of useful products of varied nature may be obtained, some being of a desirable waxy nature, others oily, others thin liquids, etc., and we have 30 invented a simple, cheap and easy method of performing this chlorination.

The hydrocarbons particularly adapted for treatment by our new process to produce derivatives of the character sought are those 35 containing a plurality of rings and solid at ordinary temperatures, such as anthracene, naphthalene, etc., their mixtures, homologues and side chain derivatives. Such waste commercial products as coal tar dead oil, 40 containing these solid hydrocarbons in solution and suspension, are also intended to be embraced within the purview of our invention. These solid aromatic hydrocarbons as such have very little value in the markets 45 at present, naphthalene being mainly used for moth balls, for disinfecting and for carbureting gas; and anthracene as a component of cheap lubricating greases. Both are of course likewise employed for making dye- 50 stuffs, but this use calls for no great amount of either; and the gross quantity so employed probably does not exceed a few tons annually. Both are, in fact, practically waste

products for which there is no market of importance, and they are, consequently, extremely cheap. Naphthalene in a pure state can be obtained for less than 2 cents a pound; pure anthracene would perhaps be even cheaper were there any demand for it. The reason for this lack of demand commercially is simply that neither body has any physical property adapting it to the common uses of life, while on the other hand as commonly met with, they have a nauseous odor and other unpleasant and dangerous characteristics, such as volatility, ready inflammability, etc. We have however discovered that by simply chlorinating these hydrocarbons by a simple, cheap and easy process, we can convert them into substances of great utility, nearly all of which are destitute of objectionable odor, volatility or inflammability. Such derivatives of naphthalene are particularly useful, and we shall speak hereinafter mainly of the treatment of naphthalene, it being understood that our process is equally applicable to anthracene and the other bodies mentioned.

Chlorin acts on naphthalene both as a substituting body, replacing hydrogen with the evolution of HCl, and as a purely additive body. Derivatives formed in either or both ways are distinguished by great stability, many withstanding very high heats, not being affected by acid, by alkali or by light or air. They are also uninflammable to an extent proportionate to the per cent. of chlorin contained, and this fact adds materially to their utility for many purposes, especially in the case of the oily and waxy bodies. Many 90 are true waxes, as for instance the hexachlorinated derivative. This substance contains over 60 per cent. of chlorin, is a soft, pliable wax, is eminently desirable in physical properties for many purposes, and is practically 95 uninflammable and unaffected by ordinary heat or chemicals. Many other of the chlorinated products are equally desirable bodies, and the number of them which can be formed by our process is almost endless, it being possible by slight alterations of the conditions to form quite different bodies. For instance, one chlorinated naphthalene is an oil which does not solidify at the coldest temperatures of winter though boiling at a temperature 100 above the melting point of tin, while an-

other, produced in nearly the same manner and containing the same per centage of chlorin, is a solid at summer temperatures.

Chlorination of organic bodies to obtain 5 definite or uniform products, especially where a far-reaching chlorination is sought, is a troublesome and uncertain operation as usually performed, and is moreover tedious and expensive. It is usually regarded as 10 necessary to employ expensive halogen carriers, such as iodin, antimony-chlorid, aluminum chlorid, etc., the bulk of which is either wasted or passes into the chlorinated body produced to contaminate it, necessitating an 15 expensive further treatment to remove and recover these chemicals. We have however discovered that if chlorin is brought into contact with these hydrocarbons in the peculiar or nascent state in which it is evolved by 20 electrolysis of ordinary metallic chlorids, and if certain precautions be taken in regard to temperature of reaction and other conditions, it is possible, easy and cheap to produce from the said hydrocarbons the valuable 25 bodies before mentioned. As to the cause of this peculiarly favorable condition of the electrolytic chlorin for producing these reactions, we are unable to speak definitely, but it is apparently due to something more 30 than a mere condition of nascentcy. Perhaps the halogen atoms or ions still retain the electric charges or other properties given them in electrolysis. We content ourselves with noting the fact without endeavoring to 35 explain it further.

Broadly stated, our method consists in electrolyzing a suitable chlorid and leading or bringing the evolved chlorin into direct contact with the hydrocarbon to be chlorinated. The chlorid may be any chlorid susceptible of electrolysis, but of course in practice sodium chlorid or potassium chlorid is generally used. The electrolytic apparatus in which the chlorin is formed may be of any 40 of the ordinary commercial types, its specific form being of but incidental importance. The hydrocarbon to be chlorinated may be placed directly in the anode chamber, either as such or in solution in a suitable indifferent body, such as chloroform, tetrachlorid of carbon or one of the oily chlorinated bodies formed by the present method. When placed in said chamber without solution, it is as a rule advisable to liquefy or vaporize it 45 by heat, to accelerate the reaction and make it permeable to the chlorin, and also to facilitate feed of the raw material. As a rule however, and especially in the case of naphthalene and anthracene, we prefer to conduct 50 the whole chlorination with the hydrocarbon in the vaporized condition and contained in a chamber structurally separate from the chlorin evolving chamber, this permitting a more exact control of temperature, admixture and amount of the reacting bodies and

other conditions of vital importance in obtaining specific products. This chlorinating chamber is preferably provided with temperature controlling means, and for many chlorinations is preferably at least partly of 70 glass to permit illumination. Actinic light is often useful in facilitating the reaction. As a source of such light, we find well adapted the ordinary electric lights, and particularly the mercury vapor lamp. We have 75 further discovered that the presence of an inorganic catalyzer is often of importance in facilitating a reaction. Such substances as iron oxid, pumice stone, boneblack, charcoal or copper oxid are useful for this purpose. 80 The use of electrolytic chlorin in a temperature-controlled lighted tube or chamber and in the presence of these inorganic catalysts, is advantageous for making chlorin derivatives of many organic bodies besides the poly- 85 ring hydrocarbons hereinbefore specified, as for instance in chlorinating benzene, toluene and other benzene derivatives, in chlorinating paraffin hydrocarbons, in forming chlorin derivatives of acids, etc. 90

In the accompanying illustration we show, more or less, diagrammatically, sundry forms of the wide variety of apparatus suitable for performing our process.

In this illustration, Figure 1 is a vertical 95 section of one form of apparatus; Fig. 2 is a vertical section of another form, and, Fig. 3 is a vertical section of a third form.

The apparatus shown in Fig. 1 is a slightly modified form of an ordinary type of wet electrolytic apparatus. This apparatus, 1, comprises a three-celled vessel, a porous diaphragm 2, separating off the chamber containing the anode, 3, from the compartments containing the cathode, a layer of metallic mercury, 4. These compartments are formed by an impervious partition, 5, extending from the top of the vessel nearly to the bottom and into the mercury layer. Through this partition extends a vertical shaft, 6, carrying a stirrer, 7, rotating in the mercury layer. Electrical contact with the mercury is made by 8. The functions of these two compartments are those usual in apparatus of this character. The metallic sodium formed in the brine 100 compartment 9 is deposited in the mercury cathode 4, the amalgam formed carried around by the stirrer into the water compartment 10 and there decomposed, forming caustic soda as usual. It may be here mentioned that the formation of caustic soda in our process aids materially in cheapening the cost of our chlorinated products. The naphthalene, etc. is fed into the anode compartment 12, through the feeding device 11 and the chlorinated products are withdrawn through 13. The specific gravity of naphthalene is but a little higher than that of water while that of the chlorinated products, though varying with the specific substances, 115 120 125 130

is distinctly higher, so that the specific gravity of the brine in the anode compartment can be adjusted so as to float unchanged naphthalene while allowing the chlorinated product to sink. In order to permit heating of the liquid sufficiently to keep the naphthalene melted, the anode compartment is provided with a steam jacket at its base, 14, said steam jacket having the usual steam inlet, 10 15, and steam outlet, 16.

Fig. 2 shows a simple wet rocking electrolytic cell of the ordinary type arranged to form and deliver chlorin into a separate chamber wherein the chlorination is performed. Apparatus 20, as a whole, is rocked by cam 21 on pivot 22, running the mercury layer, 23, between compartments 24 and 25. 15 26 and 26 are anodes; 27, the cathode. Tubes 28 take away the chlorin, being provided with elastic parts, 29, to permit the rocking of the cell. A chamber 28' may contain hygroscopic material. Tube 28 passes through the jacket 30 to permit temperature regulation, and communicates with passage 25 31. This passage, 31, is at an incline to permit heavy vapors of naphthalene or the liquid naphthalene, or, generally, both, to flow down it from melting vessel 32. A steam pipe 33, below the passage 31, permits the 30 temperature therein to be kept at a suitable point. Volatile chlorinated products, naphthalene vapor, unchanged chlorin and hydrochloric acid vapor pass up through tube 34 to the chamber 35, surrounded by cooling pipes 36, where condensable bodies are condensed, the chlorin and hydrochloric acid passing onward through pipe 37 to be condensed and separated in apparatus not here shown. The 35 non-volatile chlorinated bodies flow off 40 through pipe 38.

In Fig. 3, 40 represents a furnace with grate 41, and electrolytic cell 42, provided with an electrode 43 and a liquid metal electrode 44 and tubes 45, 46 for leading off the products 45 of electrolysis, this cell being of the usual fused-salt type. The chlorin passes out through tube 46 provided with the valve 47 and enters reaction chamber 48 where it meets naphthalene vapor coming from tube 50 49, provided with valve 50, which communicates with a naphthalene-vaporizing pot 51, mounted in furnace 52. Tube or chamber 48 is provided with the temperature-controlling jacket 53. It is usually of glass in small 55 sizes, and in larger is provided with windows through which shines the actinic light from lamp 54. Passing downward through chamber 48, the admixed chlorin and naphthalene enter a continuing chamber 55, containing 60 solid catalytic material, 56. Thence they and their reaction products enter condensing chamber 57, provided with cooling means 58, whence the condensed chlorin derivatives are removed by the gate 59. The unchanged 65 gaseous products pass out of chamber 57

through the pipe 60 into a washing chamber 61. This usually contains an oily chlorination product or other suitable body, which will remove any volatile naphthalene product. Chlorin and hydrochloric acid pass onward 70 and outward through pipe 62 into washer 63 where the latter is abstracted by solution in water while the former is removed by a suitable suction device 65 through tube 64. The chlorin may be utilized in any suitable way, 75 but preferably it is absorbed by a hot partly-chlorinated naphthalene which may later be completely chlorinated in the main apparatus.

In many reactions of chlorin on naphthalene, hydrochloric acid is produced; half the 80 chlorin going into the molecule and replacing hydrogen, and this hydrogen forming hydrochloric acid with the other half. It is one of the economies of our process that the chlorin not going into our finished chlorinated products is nevertheless recovered in a commercially valuable form. Together with the caustic soda or potash formed in the electrolytic cell, which may of course also be recovered, it aids materially in cheapening 85 the cost of our process.

In its preferred form, our process consists in electrolyzing a suitable chlorid, bringing the evolved chlorin into contact with the specified hydrocarbons in a fluid form, either 95 as liquid or vapor, regulating the temperature of the mixture and, usually, illuminating it with actinic rays, passing it through a catalyzer, separating the chlorination products and recovering the hydrochloric acid 100 formed in substitution. In its specific form, as carried out in the apparatus shown in Fig. 3, we regard it as adapted to organic chlorinations generally. The advantages of this specific form, using the hydrocarbon, etc., 105 in the vaporous form, is that it permits the use of the solid catalysts in a very efficient manner, and also permits rigid control of mixing, temperatures, proportions, etc., of chlorin and hydrocarbon. But for many 110 chlorinated products of naphthalene and anthracene, the simple treatment in the anode chamber is sufficient. It is frequently desirable to introduce merely enough chlorin into the molecule to obviate the smell, volatility, 115 etc., of the hydrocarbon, and for this purpose the comparatively low temperature reactions in the cell are best adapted. In this form, the hydrochloric acid formed is at once electrolyzed to furnish new chlorin. 120

What we regard as novel and desire to secure by Letters Patent of the United States, is:—

1. The process of forming useful products from the solid aromatic hydrocarbons which 125 consists in electrolyzing a chlorid and causing the evolved chlorin to react upon such hydrocarbon.
2. The process of forming useful products from the solid aromatic hydrocarbons which 130

consists in electrolyzing a chlorid and causing the evolved chlorin to react upon such hydrocarbon in a fluid form.

3. The process of forming useful products from the solid aromatic hydrocarbons which consists in electrolyzing a chlorid and causing the evolved chlorin to react upon such hydrocarbon in a vaporous form.

4. The process of forming useful products from naphthalene which consists in electrolyzing a chlorid and causing the evolved chlorin to react upon naphthalene.

5. The process of forming useful products from naphthalene which consists in electrolyzing a chlorid and causing the evolved chlorin to react upon naphthalene in a fluid form.

6. The process of forming useful products from naphthalene which consists in electrolyzing a chlorid and causing the evolved chlorin to react upon naphthalene in a vaporous form.

7. The process of forming useful products from the solid aromatic hydrocarbons which consists in electrolyzing a chlorid, causing the evolved chlorin to react on such hydrocarbon and separately recovering the organic reaction products and hydrochloric acid.

8. The process of forming useful products from naphthalene which consists in electrolyzing a chlorid, causing the evolved chlorin to react upon naphthalene and separately recovering the organic reaction products and hydrochloric acid.

9. The process of chlorinating solid aromatic hydrocarbons which consists in electrolyzing a chlorid, passing the evolved chlorin into a temperature-controlled chamber and admixing therewith the vapors of the body to be chlorinated.

10. The process of chlorinating organic bodies which consists in electrolyzing a chlorid, passing the evolved chlorin into a temperature-controlled chamber, admixing therewith the vapors of the organic body to be chlorinated, passing the mixture through an inorganic catalyzer and recovering the reaction products.

11. The process of chlorinating organic bodies which consists in electrolyzing a chlo-

rid, passing the evolved chlorin into a temperature controlled chamber, admixing therewith the vapors of the organic body to be chlorinated under the influence of actinic light, passing the mixture through an inorganic catalyzer and recovering the reaction products.

12. The process of chlorinating naphthalene which consists in electrolyzing a chlorid, passing the evolved chlorin into a temperature-controlled chamber and admixing therewith naphthalene vapors.

13. The process of chlorinating naphthalene which consists in electrolyzing a chlorid, passing the evolved chlorin into a temperature-controlled chamber, admixing therewith vapors of naphthalene, passing the mixture through an inorganic catalyzer, and recovering the reaction products.

14. The process of chlorinating naphthalene which consists in electrolyzing a chlorid, passing the evolved chlorin into a temperature-controlled chamber, admixing therewith naphthalene vapors under exposure to actinic light, passing the mixture through an inorganic catalyzer, and recovering the reaction products.

15. The process of forming useful products from normally solid aromatic hydrocarbons which consists in reacting with electrolytically generated chlorin upon such hydrocarbons in the fluid state and separately recovering the reaction products.

16. The process of forming useful products from naphthalene which consists in reacting with electrolytically generated chlorin upon the naphthalene while in a fluid state and separately recovering the reaction products.

In testimony whereof we hereunto affix our signatures, each in the presence of two witnesses.
